CLAIM

The design for a swinging receiver mount for vehicle, as shown and described.

DESCRIPTION

FIG. 1 is a top view of the swinging receiver mount for vehicle in a first orientation;

FIG. 2 is a front view of the swinging receiver mount for vehicle in the first orientation;

FIG. 3 is a side view of the swinging receiver mount for vehicle in the first orientation;

FIG. 4 is a perspective view of the swinging receiver mount for vehicle in the first orientation;

FIG. 5 is a top view of the swinging receiver mount for vehicle in a second orientation;

FIG. 6 is a front view of the swinging receiver mount for vehicle in the second orientation;

FIG. 7 is a side view of the swinging receiver mount for vehicle in the second orientation;

FIG. 8 is a perspective view of the swinging receiver mount for vehicle in the second orientation;

FIG. 9 is a top view of the swinging receiver mount for vehicle in a third orientation;

FIG. 10 is a front view of the swinging receiver mount for vehicle in the third orientation;

FIG. 11 is a side view of the swinging receiver mount for vehicle in the third orientation;

FIG. 12 is a perspective view of the swinging receiver mount for vehicle in the third orientation;

FIG. 13 is a top view of the swinging receiver mount for vehicle in a fourth orientation;

FIG. 14 is a front view of the swinging receiver mount for vehicle in the fourth orientation;

FIG. 15 is a side view of the swinging receiver mount for vehicle in the fourth orientation; and,

FIG. 16 is a perspective view of the swinging receiver mount for vehicle in the fourth orientation.

Portions of the article shown in broken lines represent unclaimed subject matter and form no part of the claimed design.
